UNITED STATES PATENT OFFICE.

WALLACE P. ANDRICK, OF JAMAICA, NEW YORK, ASSIGNOR TO GENERAL ACOUSTIC COMPANY, A CORPORATION OF NEW YORK.

TELEPHONE SET.

1,150,009.

Specification of Letters Patent. Patented Aug. 17, 1915.

Application filed August 22, 1914. Serial No. 858,019.

To all whom it may concern:

Be it known that I, WALLACE P. ANDRICK, a citizen of the United States, residing at Jamaica, in the county of Queens and State of New York, have invented certain new and useful Improvements in Telephone Sets, of which the following is a full, clear, and exact description.

This invention relates to a telephone set having a plurality of transmitters which are adapted to transmit their impulses to a single receiver.

The invention has special application to the type of telephone set used by deaf persons and commonly known as the "Acousticon," which in its simplest form comprises a sensitive transmitter arranged in series with an electric battery and a telephone receiver, whereby the sound waves affecting the sensitive transmitter will be intensified in transmission, and enable the deaf person who is using the receiver to distinguish sounds of an ordinary degree of loudness, such as conversations carried on in the usual speaking voice. In telephone sets of this character, it is frequently desirable to connect a plurality of sensitive transmitters in such a way that they will affect the same telephone receiver so as to collect the sound waves emanating from different parts of a room or other space. In one form of apparatus which has been used for this purpose, a plurality of transmitters have been arranged on the opposite or different faces 35 of a box-like rectangular frame; in another form a triangular box-like frame has been provided in which the sensitive transmitters are arranged upon the three upstanding faces of the same, one form of apparatus of this character being described in the patent to Turner, *et al.*, No. 846,068. It has also been found desirable to arrange two transmitters in the same plane and in a single casing whereby a pulsating current of 45 greater strength is set up in the circuit through the receiver than if a single transmitter were used, and in this manner the sounds emanating from the receiver are of increased loudness. The patent to Rhodes No. 1,039,443, discloses this form of apparatus.

The common form of telephone receivers used with telephone sets of this character has two coils which form the north and south poles of the electromagnet of the re-

ceiver, and heretofore it has been the usual, if not the invariable practice, to connect the plurality of transmitters, in shunt circuits, and to arrange the battery and coils of the telephone receiver in series in a circuit common to all of the transmitters. While this circuit arrangement works fairly satisfactorily, it has been found that by placing each transmitter in an independent circuit, which also includes one of the coils of the electromagnet of the telephone receiver, a marked increase in the loudness of the sounds emanating from the receiver is produced. This is most probably due to the fact that when the sensitive transmitters are arranged in multiple or shunt circuits, the circuit to one transmitter acts as a shunt for the pulsating current, and for this reason prevents the full strength of the pulsating circuit from passing to the coils of the telephone receiver.

The present invention therefore consists in separating the coils of the electromagnet in the telephone receiver into separate sections or windings and connecting each of these windings in a parallel circuit containing a telephone transmitter, so that each transmitter and a winding of the telephone receiver are arranged in series, the parallel branches having a common path through the electric battery.

In the accompanying drawings: Figure 1 is a front elevation of the usual form of telephone receiver; Fig. 2 is a central vertical section of the same; Fig. 3 is a diagrammatic view of the present system of connecting a plurality of transmitters to a single receiver; Fig. 4 shows a system for connecting two transmitters to a telephone receiver in accordance with the principles of this invention; Fig. 5 is a modification showing different arrangements of circuits for two transmitters, and Fig. 6 is a view showing one way in which three transmitters may be connected to the telephone receiver.

Referring first to Figs. 1 and 2, a telephone receiver of the usual type at present used is shown, which consists of the usual hollow casing 1, having a screw cap 2 with a centrally disposed aperture 3 therein. The usual diaphragm 4 is arranged between the cap and casing. In the interior of the casing 1 is a permanent ring magnet 6, which has secured to it, by means of the yoke piece 7, an electromagnet 8, comprising two coils 9 and 10, wound in opposite direc-

tion so as to constitute north and south poles when energized. These coils are adapted to act upon the diaphragm to vibrate the same when energized by the pulsating current 5 passing through the circuit.

Fig. 3 shows the coils 9 and 10 of a telephone receiver connected in series with a common circuit having a plurality of sensitive transmitters 12 and 13 arranged in parallel therewith, according to the well established practice. These sensitive transmitters are of the well known type used with "Acousticon" outfits and their special structure forms no part of the present invention, for which reason they have been illustrated only diagrammatically. As shown, the sensitive transmitter 13 is connected in shunt with the sensitive transmitter 12 by means of wires 14 and 15, while both transmitters are connected by a common circuit, to the coils 9 and 10 of the telephone receiver by means of wire 16, battery 17 and wires 18 and 19, the circuit passing through the coils 9 and 10 in series and the coils 25 being wound in such a manner that the flux set up in these coils will be in opposite directions to form the north and south poles of the electromagnet. With this form of connection, if for example the sensitive transmitter 12, is being actuated, while the sensitive transmitter 13 is at rest, which occurs when the transmitters are arranged in different planes as in the form of apparatus shown in the patent to Turner referred to, 30 the wires 14 and 15, together with the sensitive transmitter 13, forms a shunt circuit around the sensitive transmitter 12, which will permit a large part of the pulsating current to flow through the same, instead 35 of over wires 16, battery 17, to the wire 18, to the coils 9 and 10 of the receiver. The reason that part of the pulsating current takes this shunt path is in all probabilities explained by the fact that the coils 9 and 40 10 have a relatively high impedance and therefore to some extent act as a reactance coil to retard the flow of pulsating current through the same, and while although the 45 resistance of transmitter 13 is relatively high 50 yet it is non-inductive so that a relatively large amount of the pulsating current set up will pass through the same. The result 55 is a weakening of the intensity of the sounds which emanate from the receiver. This 60 same result is also apparent even if both transmitters 12 and 13 are arranged in the same plane and are both being actuated, since the circuits through each of the transmitters acts as a shunt for the other.

Fig. 4 shows one system of circuits and form of telephone receiver for avoiding shunting of the pulsating current through the circuit of the other transmitters.

As in the usual form of telephone receiver, 65 the electro-magnet consists of two coils or

windings which have been designated respectively 9^a and 10^a, but here the windings instead of being connected in series are separate. The sensitive transmitters 12 and 13 are each connected to one of these windings; 70 sensitive transmitter 12 is connected by means of wire 20 to coil 10^a, while sensitive transmitter 13 is connected to coil 9^a through wire 21. Wires 23 and 24, respectively, connect transmitters 12 and 13, in parallel to 75 a common path or circuit comprising wire 25, battery 17 and wire 26. Here the circuit again branches, the coils 9^a and 10^a being respectively connected to wire 26 by wires 27 and 28 so that the current will pass 80 through the coils in opposite directions and the flux set up in the coils will form the north and south poles of the electromagnet as in the present form of telephone receiver. It has been found that when this arrangement of circuits and form of telephone receiver is employed, the sounds emanating from the receiver are materially louder in tone than the sounds which are obtained when the present form of connection shown 90 in Fig. 3 is used. This is probably due to the fact that the entire strength of pulsating current produced by the actuation of one or both of the transmitters passes through the coils of the telephone receiver. If, for 95 example, transmitter 12 is being actuated to set up a pulsating current, the same may take two paths; one through wire 23, battery 17, wires 26 and 27, coil 10^a and wire 20 back to the transmitter; and another 100 through wire 23, 25 and battery 17 as before to wire 26, and then through wire 28, coil 9^a, wire 21, transmitter 13, and wire 24 back to wire 25. The impedance of these two circuits is practically the same as they both include one of the coils of the receiver. The major portion of the pulsating current will pass through coil 10^a as the resistance of transmitter 13, when at rest, is materially 110 greater than 12 when the same is being actuated. However, the portion of pulsating current passing through the circuit including a transmitter 13 and coil 9^a will energize this coil to aid the coil 10^a in attracting the diaphragm. If both transmitters should be actuated simultaneously, practically the same result is obtained as the pulsating current set up by each transmitter passes through its corresponding circuit.

Fig. 5 shows a modified circuit arrangement and manner of connecting separate windings of the receiver to each of the individual transmitters. Each of the sensitive transmitters 12 and 13 is connected to a 120 separate section of each of the coils and which have been designated 9^b and 10^b respectively. These sections are arranged in series and connected so that the current passes the sections in opposite directions to 125 thereby form north and south poles as be- 130

fore. The circuit for the sensitive transmitter 13 passes through wire 29 to the section 9^b and 10^b in series and then through the battery back to the transmitter by wire 39, the circuit for the sensitive transmitter 12 being similarly arranged. Therefore, in this form of the device, two duplicate sets of coils are used so that each set may be independently connected to one of the sensitive transmitters.

Fig. 3 shows one form of telephone receiver and circuit arrangement for three transmitters, the coils of the electromagnet being sub-divided as in Fig. 5 and designated 9^c, 9^d and 10^c and 10^d, respectively, the coils 9^c and 10^c being preferably of twice the resistance and number of turns as the coils 9^d and 10^d. As shown, the coils 9^d and 10^d are connected in series and wound in opposite directions and are in a separate circuit passing through transmitter 12, which circuit includes wires 31, 32, 33; the coil 9^c is connected in a separate circuit containing the sensitive transmitter 13 by wires 34, 35, 36; and the coil 10^c is connected in circuit with the transmitter 12^c by wires 37, 38 and 39. These coils are connected to their respective circuits so that the coils 9^c and 9^d will set up a flux forming the north pole of the electromagnet and the coils 10^c and 10^d will set up a flux forming the south pole of the electromagnet.

While my invention has particular adaptation to telephone sets which are used by the deaf, yet the invention is applicable to telephone sets in general in which it is desired to connect a plurality of transmitters to a single receiver and it is not my intention to be limited to the particular use specified. Moreover, various other arrangements of circuits may be provided in which each of a plurality of transmitters is con-

nected by a separate circuit to separate coils or windings of the electromagnet in the telephone receiver and it is not my intention to limit the invention to the particular circuit arrangements shown, but only by the scope of the claims appended hereto, wherein the word "windings" is deemed sufficiently broad to cover one or a plurality of coils in series with a transmitter.

I claim:

1. A telephone set comprising a telephone receiver having a plurality of separate windings, a plurality of transmitters and separate circuits respectively connecting each of said transmitters to different windings of said receiver.

2. A telephone set comprising a telephone receiver having a plurality of separate windings and a plurality of telephone transmitters, each arranged in series with different windings of said receiver.

3. A telephone set comprising a telephone receiver having a plurality of separate windings, a plurality of telephone transmitters, equal in number to the number of windings and separate circuits connecting each transmitter in series with a corresponding winding in the receiver.

4. A telephone set comprising a telephone receiver, having a plurality of separate windings, a plurality of transmitters, circuits connecting each transmitter to a corresponding winding in the receiver, said circuits being connected to said windings to produce north and south poles.

In witness whereof, I subscribe my signature, in the presence of two witnesses.

WALLACE P. ANDRICK.
